UNITED STATES PATENT OFFICE.

GUSTAVE H. SCHMIDT, OF ALHAMBRA, CALIFORNIA.

PENCIL-SHARPENING DEVICE.

Application filed June 12, 1926. Serial No. 115,586.

My invention relates to and has for its purpose the provision of a durably constructed and extremely efficient pencil sharpening device by which a symmetrically 5 tapered point can be formed upon a pencil with ease and dispatch, and which is adapted to use, although not necessarily, old safety razor blades as the cutting instrument.

A further purpose of my invention is the 10 provision of a device of the above described character in which the point is formed upon the pencil by a shaving action of a cutting blade in the direction of the pencil's length, the device being constructed to yieldably support the pencil in a manner to preclude 15 breaking of the lead during the sharpening operation; being adjustable to permit the entire length of the blade to be utilized; and being provided with means by which the 20 pencil is adapted to be rotated during the sharpening operation, so that a symmetrically tapered point will be formed upon the pencil.

I will describe only one form of pencil 25 sharpening device embodying my invention and will then point out the novel features thereof in claims.

In the accompanying drawings:

Figure 1 is a top plan view illustrating one 30 form of pencil sharpening device embodying my invention;

Figures 2 and 3 are vertical sectional views taken, respectively, on the lines 2—2 and 3—3 of Figure 1 and looking in the direction of 35 the arrows;

Figure 4 is an enlarged detail sectional view taken on the lines 4—4 of Figure 2 and looking in the direction of the arrows;

Figure 5 is a fragmentary bottom plan 40 view illustrating a portion of the mechanism for rotating the pencil.

Referring specifically to the drawings, in which similar characters of reference designate similar parts in each of the several 45 views, my invention, in its present embodiment, comprises a frame F preferably formed of metal to provide a box-like structure having a bottom 15, side walls 16, and end walls 17. The frame, in addition to providing a support for the mechanism of the device, also provides a depository for the shavings removed from a pencil and to its bottom 15 is secured a screw clamp 18 by which the frame is adapted to be clamped to 50 a suitable support. A blade holder of substantially rectangular form and designated

generally at H is slidably mounted on horizontal guide rods 19 passing freely through perforated ears 20 formed at the ends of the holder, the rods being secured at one of 60 their ends by nuts 21 to one of the end walls 17 and at the other of their ends to brackets 22 secured to the inner sides of the walls 16 by screws 23. The holder constitutes a carriage for supporting a conventional safety 65 razor blade B and to securely clamp the blade thereto with its cutting edge projecting therefrom, a pair of upstanding pins 24 and a threaded stud 25 are secured to the holder and are adapted to be received in the 70 usual openings provided in the blade as well as in similarly spaced openings formed in a clamping plate 26. A handle 27 threadedly engages the stud 25 and operates to securely clamp the blade between plate and 75 holder and also serves as a means by which an operator can readily reciprocate the holder upon the guide rods 19. It will be noted that the top surface of the holder and the bottom surface of the plate are curved 80 transversely so that when the blade is clamped between the two it is flexed transversely to present its cutting edge downwardly at a slight angle.

For supporting a pencil with its end to 85 be sharpened in an upwardly inclined position with respect to and in the path of movement of the cutting blade so that upon reciprocation of the latter a shaving of the pencil in the direction of its length will be 90 effected, a clamping member C is rotatably mounted in a bracket 28. The clamping member is of tubular form to freely receive a pencil P and to securely clamp the pencil 95 therein the member is provided externally at one end with tapered threads 29 and is slotted longitudinally at intervals to provide flexible sections 30 which are adapted to be constricted to grip the pencil by means of a knurled nut 31 threadedly engaging the 100 threads 29. The bracket 28 is supported for sliding movement in the frame by means of a threaded shaft 32 threaded through an opening formed in the bracket and rotatably mounted in the side walls 16. The shaft is 105 fixed against longitudinal movement by a nut 33 and an operating knob 34 secured to the shaft and disposed exteriorly of the frame. By rotation of the knob it will be clear that the bracket 28 and consequently the clamping member C will be adjusted transversely with 110 respect to the path of movement of the cut-

ting blade so that in the event one portion of the blade becomes dull, the pencil can be moved to occupy another position along the length of the blade's cutting edge, thus 5 permitting the entire length of the latter to be utilized.

In addition, the bracket 28 is capable of being rocked slightly upon the shaft 32 against the tension of a flat spring 35 10 secured to the bracket and bearing against the bottom 15 of the frame so that in the event too heavy a cut is being taken upon the pencil, the latter can yield and the danger of breaking the pencil or cutting blade thus 15 minimized.

To rotate the pencil P slightly upon each reciprocation of the holder H and thus present a new surface of the pencil to the blade at each cutting stroke thereof the 20 following mechanism is provided. A cam member 36 in the form of a flat bar having a cam surface 37 is secured to the holder exteriorly of the frame F by means of threaded studs 38 projecting through a slot 39 formed in one of the side walls 16 and threaded into the holder. A rack bar 40 is 25 slidably mounted in the side walls 16 and adjacent one of its ends is provided with a transverse recess 41, the bar being normally urged to a position in which the recess is 30 out of alignment with the cam member by means of an expansible spring 42 interposed between the side wall 16 and a pin 43 secured to the bar. The rack bar has meshing engagement with a gear 44 of ring form 35 mounted on the clamping member C and for transmitting rotative movement of the gear to the clamping member in one direction only a clutch K is interposed between the two. 40 In this instance the clutch comprises a collar 45 welded or otherwise secured to one of the flexible sections 30 and provided upon its periphery with wedge shaped pockets 46 (Figure 4) receiving balls 47 which upon 45 motion of the gear 44 in the direction of the arrow are wedged into the smaller end of the pockets and into locking engagement with the gear. It will be noted from Figure 2 that the pockets are also oppositely 50 tapered transversely so that lateral displacement of the gear from the ring is prevented.

In operation with the frame F clamped to a support and the blade holder H occupying the position shown in Figure 1 a pencil is inserted into the clamping member C a sufficient distance to dispose the end to be sharpened in the path of movement of the cutting blade B. The nut 31 is now tightened 55 to securely clamp the pencil in the member and the holder moved manually in the direction of the arrow (Figure 1) by means of the handle 27 to effect a shaving cut upon the pencil. Adjacent the end of the 60 return movement of the holder, the cam sur-

face 37 of the cam member 36 engages the wall of the recess 41 (Figure 5) to thereby move the rack bar 40 in the direction of the arrow and through the medium of the gear 44 and clutch K a partial rotation of the 70 clamping member C and consequently the pencil is effected, thus presenting a new surface of the latter to the blade upon its succeeding cutting stroke. As the cam surface 37 moves out of engagement with the recess 75 41 during the next cutting stroke of the blade the spring 42 returns the rack bar 40 to its initial position limited by the stop pin 48 thus reversely rotating the gear 44 which by virtue of the uni-directional clutch K moves 80 freely on the collar 45. It will thus be clear that upon each reciprocation of the holder a partial rotation of the pencil is accomplished so that a point of symmetrically tapered form 85 will ultimately be formed thereon. 95

Although I have herein shown and described only one form of pencil sharpening device embodying my invention, it is to be understood that various changes and modifications may be made therein without departing from the spirit of the invention and the spirit and scope of the appended claims. 90

I claim as my invention:

1. A pencil sharpening device comprising a box-like structure having an open top, 95 sides and a closed bottom and constituting a frame adapted to be clamped to a support, guide rods secured to the frame, a manually operable blade holder comprising a carriage slidably on said rods, upstanding pins secured to said carriage adapted to be received in openings formed in a cutting blade, a blade clamping plate having openings registering with said pins, a handle threaded on one of said pins and adapted to clamp the cutting blade between the plate and carriage, a bracket adjustable in the frame transversely of the direction of movement of the carriage, a tubular clamping member rotatable in the bracket and adapted to receive and clamp against movement therein a pencil to be sharpened, and means adapted to be operated by the carriage for imparting a progressive axial feed to the clamping member for the purpose described. 105

2. A pencil sharpening device comprising a frame, a blade holder including a carriage mounted for reciprocatory movement in the frame, a bracket supported by the frame, a tubular clamping member rotatably mounted in the bracket and adapted to receive and support a pencil in a position to be angularly shaved in the direction of its length by a cutting blade, a gear mounted on said clamping member, a clutch interposed between said gear and clamping member for operatively connecting the two upon rotation of the gear in one direction only, a rack bar meshing with said gear and having a transverse recess, said bar mounted for movement in the 110 115 120 125 130

frame from one extreme position to another extreme position, means for normally urging the bar to one of its extreme positions, and a member secured to the carriage having 5 a cam surface adapted to be received in said recess during the return stroke of the carriage for moving the bar to its other extreme position against the action of its urging means whereby through the medium of said 10 gear and clutch partial rotation of the clamping member will be effected.

3. A pencil sharpening device comprising a pencil support, a blade holder mounted for movement to effect a shaving cut by its blade 15 upon a pencil in the support and means for mounting said support to yield when through improper positioning of the pencil with respect to the blade, the latter attempts to effect a relatively heavy cut, to thereby 20 prevent the blade from completing the relatively heavy cut.

4. A pencil sharpening device comprising a blade holder mounted for movement, means including a rotatable member in 25 which a pencil is adapted to be supported in a position to be shaved angularly in the direction of its length by a blade in the holder, and means controlled by the movement of the holder for partially rotating said member progressively and comprising a rack bar 30 mounted for movement, a gear meshing with the rack bar, co-acting means on the holder and rack bar for effecting movement of the latter to rotate the gear, and a clutch for 35 operatively connecting the gear to the member during rotation of the gear in one direction.

5. A pencil sharpening device comprising a frame, a blade holder including a carriage 40 mounted for reciprocatory movement in the

frame, a bracket supported by the frame, a tubular clamping member rotatably mounted in the bracket and adapted to receive and support a pencil in a position to be angularly shaved in the direction of its length by a cutting blade, a gear rotatably mounted on said clamping member, a uni-directional clutch for operatively connecting the gear to the member, a rack bar meshing with said gear, said bar mounted for movement in the frame, and normally urged to one extreme position, and cam means secured to the carriage adapted to engage and actuate said bar at one end of the stroke of the carriage and through the medium of said gear and clutch 55 to effect partial progressive rotation of the clamping member.

6. A pencil sharpening device comprising a frame, a blade holder including a carriage mounted for reciprocatory movement in the frame, a bracket supported by the frame, a tubular clamping member rotatably mounted in the bracket and adapted to receive and support a pencil in a position to be angularly shaved in the direction of its length by a cutting blade, and means controlled by the movement of the carriage for progressively rotating the clamping member, said bracket being adjustable in the frame transversely 60 with respect to the length of the cutting blade and said adjustment comprising a threaded shaft threadedly engaging the bracket and rotatably mounted in the frame, and an operating knob secured to the shaft 65 by which the latter can be rotated to feed the bracket along its length to thereby permit the entire length of the blade's cutting 70 edge to be utilized.
